UNITED STATES PATENT OFFICE.

JOHN E. DONOVAN, OF CINCINNATI, OHIO.

VAPOR-BURNER.

SPECIFICATION forming part of Letters Patent No. 283,977, dated August 28, 1883.

Application filed December 29, 1880. (Model.)

To all whom it may concern:

Be it known that I, JOHN E. DONOVAN, of Cincinnati, in the county of Hamilton, and in the State of Ohio, have invented certain new and useful Improvements in Vapor-Burners; and I do hereby declare that the following is a full, clear, and exact description thereof, reference being had to the accompanying drawings, making a part of this specification, in 10 which—

Figure 1 is a perspective view of my improved burner arranged for use. Fig. 2 is a vertical central section of the same upon a line lengthwise of the burner; and Fig. 3 is a section upon line $x x$ of Fig. 2.

Letters of like name and kind refer to like parts in each of the figures.

The design of my invention is to increase the efficiency of vapor-burners, and to render 20 the same more uniform in operation; to which end it consists, principally, in the means employed for equalizing and controlling pressure within the burner and reservoir, substantially as and for the purpose hereinafter specified.

25 In the annexed drawings, A represents a reservoir having any desired form, which is closed at its upper end, and at its lower end is secured to or upon a metal block or elbow, B, that in turn rests upon and is secured to a suitable supporting-base, C.

Formed within and extending downward from the upper end of the elbow B are two openings, b and b' , which, at their lower ends, are intersected by a horizontal opening, b'' , that extends from one side of said elbow inward through said opening b' to said opening b , and from its outer end inward to said opening b' has a considerably larger diameter than from thence to its inner end. Within the outer 35 largest portion of the opening b'' is inserted and secured one end of a tube, D, while within the inner smaller portion of said opening is secured a second smaller tube, E, which passes outward through said tube D and has its outer 40 largest portion of the opening b'' inserted and secured one end of a tube, D, while within the inner smaller portion of said opening is secured a second smaller tube, E, which passes outward through said tube D and has its outer

45 end upon a line with or slightly beyond the outer end of the latter. The space between the interior of said tube D and the exterior of the tube E is loosely filled with wire-cloth F. From the upper end of the vertical opening b a tube, G, extends upward nearly to the upper end of the reservoir A, while within the opening b' is placed a stop-cock, consisting of a tapering

valve, H, which is formed upon the end of a screw-threaded stem, h, and, passing horizontally inward through a packed opening provided in the side of the elbow, fits within a tapering seat that is formed in said elbow and intersects said opening b' . The outer end of the tube D is secured within a burner, I, and communicates with a passage, i, that from thence extends downward, and then horizontally rearward, and at its rear end receives an elbow-section, K, that is provided with a passage, k, that from said passage i extends rearward, and thence vertically downward. The 55 upper open end of the passage i is inclosed by means of a screw-plug, L, while the lower end of the passage k is in like manner inclosed by means of a similar screw-plug, M, and at or near the lower end of the elbow-section K is 60 provided a cup, k', which surrounds and is secured upon the same.

Between the upper and lower ends of the elbow-section K is a horizontal cylindrical enlargement, k'' , which is principally located upon 75 the side toward the reservoir A, and is provided with an axial opening, k^3 , that is threaded in rear of the opening k , and in front of said opening has an outwardly-decreasing diameter, and at its end is very small.

Passing through the supporting-base C is a 80 rod, N, which, near its outer end, is provided with a screw-thread that corresponds to and closely fills the threaded portion of the opening k^3 , and at its end is tapered to fit within 85 and fill the tapering portion of said opening. If the rod N is turned backward, its end n will be partly or wholly withdrawn from the tapering portion of the opening k^3 , so as to open communication through the latter with the 90 passage k , while by turning said rod forward its said tapered end or valve n may be caused to partly or entirely fill said opening, which thus becomes a valve-seat, and thus partially 95 or wholly cuts off communication with said passage k .

Directly in front of the opening k^3 , within the burner I, is provided an opening, i' , which has several times the diameter of the passage i , and decreases in diameter from its rear end 100 to its front end, at which latter point said opening connects with and opens into a tube, O, that from thence extends forward, and then in a curve upward. The tube O is consider-

ably larger in diameter than the opening i' , and its rear end is provided with several longitudinal slits or openings, o , which are arranged at equidistant points, and operate to admit air 5 to the interior of said tube.

The device thus constructed operates as follows, viz: The reservoir A is filled with the liquid to be vaporized to or near the upper end of the tube G, and the valve H is then 10 opened, so as to permit a quantity of such liquid to pass downward to the burner through the space between the tubes D and E, after which said valve is closed. The valve n is then opened sufficiently to permit the liquid 15 to escape from the opening k^3 and partly fill the cup k' , after which said valve is closed and said liquid ignited. The heat given off from the burning liquid within the cup k' raises the temperature of the elbow-section K 20 and the rear end of the main section I of the burner sufficiently to cause the liquid within said parts to become vaporized, after which the valve n is opened and said vapor permitted to escape from the opening k^3 into the opening 25 i' , where it becomes ignited, and, passing into the tube O, mixes with air that enters through the openings o and burns with a steady heating-flame. The heat of the flame within the opening i' is communicated to the burner I, and 30 serves to maintain the vaporization of the fluid within the latter after all fluid within the cup k' has been consumed. After the vapor has been produced and ignited the upper valve, A, is opened sufficiently to permit the passage 35 of the necessary quantity of liquid to maintain the supply of combustible vapor, while, by the adjustment of the valve n , the amount of vapor consumed, and consequently the size of the flame, may be regulated. The wire-cloth 40 filling F between the tubes D and E checks the flow of fluid and causes the same to be delivered to the burner in a steady uniform quantity. In consequence of the tube E, openings b' and b^2 , and tube G free communication 45 is afforded between the burner I and the upper portion of the reservoir A, so that all surplus gas produced within said burner may pass into said reservoir, whereby the pressure within said parts is equalized, and all impediment 50 from such cause to the natural flow of the liquid is prevented.

In order that all danger from undue pressure within the apparatus may be avoided, the

screw cap or plug P, which closes the filling opening a within the upper end of the reservoir A, is provided with a round tapering opening, p , which has its smallest end downward and receives a correspondingly-shaped valve, Q, that is provided above and below with a stem, q . The lower end of the valve-stem q is threaded and supplied with a nut, R, and between said nut and the lower end of the plug P is placed a volute spring, S, that, by means of said nut, may be caused to draw downward upon the valve Q with any desired 65 degree of force. The valve Q being adjusted to the desired pressure, any excess of such pressure will cause said valve to rise, so as to permit of the escape of gas, the operation being similar to that of an ordinary safety-valve. 70

In consequence of the inclosure of the vapor-conducting pipe within the pipe used for supplying liquid to the burner the mechanism is rendered compact, and is not liable to disarrangement; and, in addition thereto, the vapor 75 in passing to the reservoir is protected from material loss of temperature and consequent condensation, such heat as is given off from said vapor being absorbed by the surrounding liquid. 80

Having thus fully set forth the nature and merits of my invention, what I claim as new is—

1. In a vapor-burner having supply-tubes, the combination of oil-passage k and needle-valve n , the mixing-chamber O and the burner-section I, and expansion heating-chamber i , located between the oil-passage and mixing-chamber and supply-tubes, so that the expansion heating-chamber will connect with the supply-tubes and oil-passage k , and the opening i' of the burner-section will be between the needle-valve and mixing-chamber, substantially as described. 85

2. In a vapor-burner, the combination of 90 tubes D and E, reservoir A, provided with tube G, and the intermediate separate elbow, B, provided with passages b' , connecting with tubes D and E, substantially as described. 95

In testimony that I claim the foregoing I have hereunto set my hand this 24th day of December, 1880.

JOHN E. DONOVAN.
